(57) **CLAIM**

The ornamental design for a hat, as shown and described.

DESCRIPTION

FIG. 1 is a perspective view of the hat showing my design;

FIG. 2 is a front view of the hat of FIG. 1;

FIG. 3 is a right side view of the hat of FIG. 1;

FIG. 4 is a left side view of the hat of FIG. 1;

FIG. 5 is a back view of the hat of FIG. 1; and,

FIG. 6 is a top view of the hat of FIG. 1.

The broken lines showing environmental structure are for illustrative purposes only and form no part of the claimed design.

1 Claim, 6 Drawing Sheets
